UNITED STATES PATENT OFFICE.

AUGUST R. SCHOENKY, OF SOMERVILLE, MASSACHUSETTS, ASSIGNOR TO THE REECE SHOE MACHINERY COMPANY, OF BOSTON, MASSACHUSETTS, A CORPORATION OF MAINE.

SEWING-MACHINE.

1,124,535.

Specification of Letters Patent. Patented Jan. 12, 1915.

Application filed January 9, 1913. Serial No. 740,929.

To all whom it may concern:

Be it known that I, AUGUST R. SCHOENKY, a citizen of the United States, residing at Somerville, in the county of Middlesex and State of Massachusetts, have invented certain new and useful Improvements in Sewing-Machines, of which the following is a specification, reference being had therein to the accompanying drawing.

10 My invention relates to sewing machines and more particularly to that class of machines wherein an upper thread is fed from a shuttle and a lower thread is manipulated in conjunction therewith so as to interlock 15 the two threads in the sewing operation. The present invention is herein shown for convenience as applied to the class of machines used in the manufacture of shoes by the welt system wherein the outsole and welt 20 are sewed together. An example of that class of machine is illustrated in my prior application, Serial No. 722,300, filed September 25, 1912.

An object of the present invention is to 25 generally improve the construction and operation of sewing machines of the class above referred to.

A particular object of the present invention is to afford an improved mechanism for 30 manipulating the under thread, the same possessing greater reliability in operation, simplicity and durability.

Another object hereof is to improve and render positive the feeding of under thread 35 as required for each stitch in conjunction with the take-up mechanism therefor.

Other objects and advantages pertaining to the present invention will appear in the hereinafter following description or will be 40 apparent to those skilled in the art.

To the attaining of such objects and advantages, the present invention consists in the novel combinations, arrangements, devices and parts set forth, described and illustrated in the following description and accompanying drawings.

I will first describe one form of machine embodying my improvements and will thereafter point out the novel features in the 50 claims.

In the accompanying drawing forming a part hereof Figure 1 is a left elevation of a sole sewing machine embodying my inven-

tion, or rather the upper portion of such a machine, the supporting post 1 being broken off as shown instead of being illustrated as extending to the floor. Fig. 2 is also a left hand elevation, but only of the special parts to which the claims are directed and on an enlarged scale. Fig. 3 is a front elevation of some of the parts seen in Fig. 2. Fig. 4 is a left hand elevation partly in section upon the plane 4—4 of Fig. 3. Fig. 5 is a similar view on the plane 5—5 of Fig. 3. Fig. 6 is a central longitudinal section on the plane 6—6 of Figs. 2 and 4.

Similar numbers of reference designate corresponding parts in the several figures of the drawings.

While a complete description of the general parts of the machine is not necessary, I will refer to some of them for the purpose of showing the general arrangement of the parts and their relation to the thread mechanism. It will be understood that the machine illustrated in Fig. 1 is a waxed thread sewing machine of the class referred to. Extending upwardly from any convenient base is post 1 supporting at its upper end the head casting 2, which will be of a complicated nature unnecessary to describe, it affording support for various parts of the machine. The main shaft 3 is in the upper part of the machine, extending from left to right and having bearings in hangers 4, and the shaft may be driven by pulley or otherwise. Carried on the shaft are the necessary cams for the machine, including the cam 8 shown in Fig. 1 and a similar cam concealed behind cam 8 the groove of which is seen in 90 dotted lines.

The shuttle case casting 10 may be located as usual and it will be understood that the shuttle, which is of the circular type, contains a bobbin, the latter being retained in 95 place by the bobbin retainer 14, which latter the operator may open at will by depressing the knob 149 as in said prior application.

In a waxed thread machine it is necessary to keep the parts heated and for this purpose 100 steam pipes 15 are shown in various locations, and steam containers or boxes, for example the steam box 16 for heating the shuttle, the steam box 17 for heating the take-up and the steam box 18 for heating the 105 auxiliary take-up.

As usual the machine may have a work support 21, and coöperating with it a presser foot 23 located above the work, and an awl 24 penetrating the work from beneath, a 5 needle 25 penetrating it from above, and a needle guide (not shown). Beneath the work may be the parts including the looper 28 for forming loops in the under thread, and coöperating parts above the work will 10 be understood. Before the thread passes to the looper 28 it is engaged by an auxiliary take-up 30, the main take-up 31 and the thread lock or locking wheel 32. The course of the thread may be from a wax pot at 15 the rear, it passing forwardly and making somewhat over a complete turn around the groove in the wheel 32 thence to the auxiliary take-up 30 and around it, and thence around the wheel on the main take-up and 20 thence to the looper 28.

Referring again to the main shaft and the cams thereon, a cam groove 33 is seen in dotted lines in Fig. 1, this cam having connections which will be hereinafter described 25 for oscillating the take-up shaft. The cam 8 has a groove 42 for actuating the needle guide and a groove 43 for giving oscillatory motion to the shuttle. The connections between cam 42 and the needle guide may 30 comprise a bell crank lever 101, having a rack 103 at its forward end for driving the pinion on the needle guide shaft. The cam 43 may actuate the shuttle through a cam lever 59 having a toothed rack at its forward end connected through gears and pinions with the shuttle driver.

The reference numerals as hereinbefore used correspond with those in my said prior application. Those hereinafter used do not 40 so correspond.

The to-and-fro moving take-up is shown in the form of an oscillating arm 31 which may have a pulley 45 at its extremity, and the arm 31 may be secured to a take-up 45 shaft 46. In order to oscillate the shaft for causing the take-up movements the shaft may have at its further end an arm 47 shown in dotted lines, connected by a link 48 to the lower end of a cam lever 49 (see 50 Fig. 1) which is pivoted intermediate its ends at 50 and which at its upper end has a stud 51 engaging the cam groove 33 before mentioned. By this train of parts the rotation of the main shaft causes the oscillation 55 of the take-up shaft.

Referring to the auxiliary take-up 30, it may consist of a short oscillating arm movable between an upper stop 34 and a lower stop 35, and a spring 36 may be used to press 60 the auxiliary take-up toward its upward position.

Referring now to the thread lock 32, it is shown in the form of a locking wheel of the type having a peripheral V-groove with 65 cross perforations to give the wheel a grip-

ping hold upon the thread. I find that this absolutely locks the thread when the wheel is held from rotation.

As will be seen the lock wheel and the take-up shaft are concentrically mounted. 70 This arrangement may be effected by means of a fixed sleeve 52 projecting leftwise from the frame of the machine (see Fig. 3). The take-up shaft 46 passes within the sleeve 52. The lock wheel 32 and its integral sleeve or 75 hub 53 surround the sleeve 52. The take-up arm being secured on the end of its shaft by a locking nut all of the parts are maintained in proper relative position.

According hereto the lock wheel 32 is 80 adapted to be normally held stationarily or locked fast by locking devices operating upon the hub 53 of the lock wheel. These locking devices may for convenience be constructed as follows:

An annular casting 54 surrounding the lock wheel hub is rendered relatively fixed in position by means of a toothed extension 55. This annular casting or sleeve 54, which is 90 shown in cross section in Fig. 5, is provided with a tangential bolt passage as shown, it being closed by a plug 56 at the left end and containing a friction lock or bolt 57 which is pressed forwardly by springs 58.

The forward movement of the thread 95 wheel 32 is a leftwise rotation, therefore the friction bolt 57 effectively locks the wheel against advance, the bolt having an inclined or wedge surface 60, which causes the parts to bind and prevent improper or excessive 100 movement.

For unlocking the thread wheel so as to permit feeding movement at the proper times, the wedge or bolt 57 may be provided at its outer end with a contact or roller 61 105 adapted to be engaged and operated by a contact or cam 62 on the take-up in a manner that will hereinafter appear.

Having described the mode of locking and unlocking the thread feeding device or 110 thread wheel I will now describe the manner of positively advancing it at the proper time so as to feed a definite amount of thread for each stitch to be formed.

Surrounding the thread wheel hub 53 and 115 locked alongside of the annular casting 54 is a second annular casting or sleeve 63 which may be termed the feed sleeve. This, as shown in Fig. 4 is provided at one side with a recess 64 in which is mounted a friction pawl or grip 65, in such a way that normally the pawl is out of engagement with the wheel hub 53, but when lifted is thrown into gripping engagement so that further lifting manifestly causes the leftwise rotation of the hub and the consequent 120 advance of the thread wheel. The normal position of these parts is as shown in Fig. 4 in which is seen a spring 66 tending to return the parts to normal position, this 125 130

spring being secured at its forward end to a lug 67 forming part of the sleeve 63 and said lug 67 cooperating with a stop 68 formed on the casting 54. Whenever the sleeve 63 is rotated leftwise and released the spring 66 brings the stop 67 back into contact with stop 68.

For the purpose of lifting the pawl 65 to effect the described operations a contact or screw 69 may be employed, this being shown mounted on the take-up 31. This contact 69 is in the form of a screw for the purpose of adjustment, and a lock nut 70 is shown for securing it in adjusted position.

The operation of the parts as so far described may be as follows: It will be understood that the take-up arm moves a given distance upwardly to permit the interlocking of the two threads at each stitch, and then downwardly to take up the excess thread, and this taking up action continues through the entire down stroke of the take-up. After each stitch and before the next one a given amount of thread must be provided for the subsequent stitch. Ordinarily this additional thread is provided through the pull of the thread itself upon its holding or guiding devices. According to the present improvement, however, the exact amount of thread required is positively fed from the locking device or wheel. I prefer to effect this during the upward or return stroke of the take-up. Thus, before the take-up reaches its highest position two things occur. First, the contact or cam 62 engages the lock bolt 57 to force it rearwardly and thus unlock the wheel 32. Thereupon the contact or screw 69 engages and presses upwardly the pawl or grip 65, lifting it and causing it to grip and to rotate leftwise the hub 53 of the lock wheel. The grooves of the lock wheel, engaging the thread by a non-slipping engagement, draw thread from the supply and force thread toward the auxiliary take-up. The quantity of thread thus advanced is thereby made available for the subsequent stitch. This quantity is regulated by adjusting the screw contact 69. The sooner the screw contacts with the pawl 65 the more thread is fed at each stitch. On the subsequent downward movement of the take-up the pawl 65 is disengaged and the locking bolt 57 is disengaged, thus restoring the original locked condition of the wheel 32.

In addition to the regulation already referred to another regulation of the thread feed is rendered possible through the simultaneous adjustment about the take-up shaft 46 of the two annular castings 54 and 63. Thus the toothed extension 55 engages the teeth of a pinion 71 which in turn engages a second pinion 72 upon whose shaft is an arm 73 connected by a link 74 to the presser foot lever 75 (see Fig. 1). By this arrange-

ment any variation in the thickness of the work causes an automatic readjustment of the presser foot and, through the mechanism described, a readjustment of the stitch as required by the change in the work's thickness.

It will thus be seen that I have described a machine embodying the principles of the present invention and possessing the advantages referred to. Since the described mechanism might be indefinitely varied as to details without departing from the principles involved, I do not wish to be restricted to the particular details recited except in so far as they are referred to in the appended claims.

What I claim and desire to secure by Letters Patent is:

1. In a sewing machine the combination of a take-up, means for moving the take-up through its take-up stroke and return stroke, means for locking the thread against advancing from the supply, and means whereby the take-up on its return stroke first releases said locking means and then advances the thread.

2. In a sewing machine the combination of a take-up, means for moving the take-up through its take-up stroke and return stroke, means for locking the thread against advancing from the supply, means for advancing the thread from the supply, and connections whereby the take-up on its return stroke first releases said locking means and then operates said advancing means.

3. In a sewing machine the combination of a to-and-fro moving take-up, a movable thread lock, means for reciprocating the take-up through its take-up stroke and return stroke, and mechanical connections by which the take-up upon each return stroke releases and then advances the thread lock, comprising a contacting means carried by the take-up coöperating with the thread lock.

4. In a sewing machine the combination of a to-and-fro moving take-up, a movable thread lock, means for reciprocating the take-up through its take-up stroke and return stroke, and connections by which the take-up upon each return stroke advances the thread lock, comprising contacts operated by the take-up, and means for relatively adjusting the contacts to vary the amount of thread measured.

5. In a sewing machine the combination of a to-and-fro moving take-up, a movable thread lock, means for reciprocating the take-up through its take-up stroke and return stroke, and connections by which the take-up upon each return stroke advances the thread lock, comprising contacts operated by the take-up, and means for relatively adjusting the contacts to vary the amount of thread measured controlled by a

work engaging member in accordance with the thickness of the work.

6. In a sewing machine the combination of a to-and-fro moving take-up, a movable thread lock, means for actuating the take-up, and connections by which the take-up at each stitch advances the thread lock, said thread lock having a locking device and an advancing device, the connections from the take-up acting to first open said locking device and then move said advancing device.

7. In a sewing machine the combination of an oscillating take-up, a movable thread locking wheel, means for actuating the take-up to oscillate over a fixed path to take up thread and return, and connections from the take-up for positively advancing said wheel, on each return stroke of the take-up.

8. In a sewing machine the combination of an oscillating take-up, a movable thread locking wheel, means for actuating the take-up to oscillate over a fixed path to take up thread and return, and connections from the take-up for positively advancing said wheel, on each return stroke of the take-up, said connections comprising an adjustable contact.

9. In a sewing machine the combination of an oscillating take-up, a movable thread locking wheel, means for actuating the take-up to oscillate over a fixed path to take up thread and return, and connections from the take-up for positively advancing said wheel, on each return stroke of the take-up, said connections comprising an adjustable contact and means for unlocking the wheel before said contact comes into play.

10. In a sewing machine the combination of an oscillating take-up shaft, a take-up thereon, a fixed sleeve about said shaft, a movable thread locking wheel having its hub about said sleeve, a hub clamp about said hub, a wheel advancing device about said hub, and means carried by said take-up for operating said clamp and advancing means in harmony.

11. In a sewing machine the combination of an oscillating take-up shaft, a take-up thereon, a fixed sleeve about said shaft, a movable thread locking wheel having its hub about said sleeve, a hub clamp about said hub, a wheel advancing device about said hub, and means carried by said take-up for

operating said clamp and advancing means in harmony, and means for adjusting said operating means to regulate the thread feed.

12. In a sewing machine the combination of an oscillating take-up shaft, a take-up thereon, a fixed sleeve about said shaft, a movable thread locking wheel having its hub about said sleeve, a hub clamp about said hub, a wheel advancing device about said hub, and means carried by said take-up for operating said clamp and advancing means in harmony, and means for adjusting said operating means to regulate the thread feed, and other means for automatically simultaneously adjusting said clamp and advancing means to vary the amount of feed.

13. In a sewing machine the combination of a thread gripper, a gripper actuating means for positively advancing the thread, a gripper locking means for preventing thread advance, a take-up movable through its take-up stroke and its return stroke, and connections whereby the take-up on its return stroke first releases said locking means and then operates said actuating means.

14. In a sewing machine the combination of a rotatable thread wheel adapted to peripherally grip the thread at a point between the thread supply and take-up, a take-up movable through its take-up stroke and return stroke, locking means adapted to lock said wheel and thereby the thread, and connections whereby the take-up first releases said locking means and then advances said wheel a predetermined amount.

15. In a sewing machine the combination of a rotatable thread wheel having a peripheral V-groove interrupted by lateral recesses along the groove base adapting it to securely grip the thread at a point between the thread supply and take-up, a take-up movable through its take-up stroke and return stroke, locking means adapted to lock said wheel and thereby the thread, and connections whereby the take-up first releases said locking means and then advances said wheel a predetermined amount.

In testimony whereof I affix my signature in presence of two witnesses.

AUGUST R. SCHOPENK.
